UNITED STATES PATENT OFFICE.

ALBERT C. BURKE, OF LA CROSSE, WISCONSIN.

CAN OPENER.

Application filed July 16, 1921. Serial No. 485,290.

To all whom it may concern:

Be it known that I, ALBERT C. BURKE, a citizen of the United States, residing in the city of La Crosse, county of La Crosse and State of Wisconsin, have invented new and useful Improvements in Can Openers, of which the following is a true specification, reference being had to the accompanying drawings.

10 The invention has reference to can openers.

An object of the invention is to produce an improved can opener, convenient, simple, and adapted to a wide variety of uses.

15 Another object of the invention is to produce a can opener that is adapted to make an opening in sealed cans for the pouring out of the liquid contents thereof, and at the same time make another opening or a vent 20 in the can for the ingress of air while the contents of the can are being removed, to facilitate the emptying of the can, by a single stroke of the opener; to provide a support for the opener that is adapted to different heights of cans; and also to provide 25 an opener that shall be adapted to the ordinary uses of a can opener of the ordinary type, and that may also be utilized for making mere punctures in cans adapted to permit of the outflow of liquids without the use 30 of hammers, and to so form the opening made that the entire contents of the can will flow out without restriction of flanges made 35 interiorly in the can during the process of making the opening.

In the drawings, Fig. 1 is an elevation of the device embodying my invention as applied to use with very short cans, showing the device mounted upon its support in position to be forced downward to make a puncture in the top of a can; Fig. 2 is a perspective view of the device used in making a discharge opening at the edge of the top of a can of medium size, and a vent for the ingress of air to permit of rapid outflow of the contained liquid, the cutting blades therefor being shown as having made the respective openings; Fig. 3 shows the device as applied to a large-sized can, mounted upon its support, but making a mere vent in the middle of the top of the can; Fig. 4 is a perspective view of the device separated from its standard; Fig. 5 is a detail in partial cross-section of one end of the device; and Fig. 6 is a detail in cross-section of an upper corner of a can, showing the nature of the opening made

therein by the use of the cutter for making a discharge opening.

In the drawings the numeral 10 indicates a support or standard for the cutting or slitting tool proper, the support standing substantially vertically, and having a horizontal bent portion 10^a at its lower end, upon which a can may be rested during the use of the device, the upright portion of the support having a plurality of holes 10^b therethrough for receiving a round lug or pivot pin 11^a on the end of the cutting tool proper.

The letter A indicates a large-sized can, the letters AA a medium sized can, and the letter B a smaller sized can; A² indicates the top wall, A⁷ the vertical wall, A³ the usual flange rising above the top wall of sealed cans, A⁴ the inward or downward flange formed when the wall of the can is bent downward from the outside, A⁵ is another or end flange formed by the outward radial pressure of the appliance, as shown later herein, and A⁶ is the corner of the opening left between the ends of the flanges A⁴ and A⁵.

I have embodied my invention in a tool comprising the vertical standard 10, against which, in use, the vertical wall of the can is closely placed, as shown in Figs. 1 and 2, the lower end of the standard being bent laterally to form the base part 10^a as above described. In this way, the cans can be properly held to position while being opened.

The numeral 11 indicates the lever part of the appliance proper, having at one end a member generally designated by the numeral 12, the latter being rigidly secured to the lever 11 by rivets 12^a. 11^b indicates a stud or pivot projecting laterally from the side of the lever in front of the member 12, to be inserted in one of the holes 10^b as occasion may require as a support for the end of the lever on the standard. The member 12 is, as shown, provided with a prong 13 which is bent around in semi-loop form, to provide an edge 13^a to rest upon the top of the can when the slitting knife 14, that projects practically parallel with the lever, is used for cutting a long slit in the top of the can, as, when cutting through the top wall near the rim A³ so that the top may be folded back out of the way, or entirely removed from the can. When used for this purpose the tool is used in the position shown in Fig. 4.

Upon the opposite side of the member 12

is formed another cutter or puncture point 15, having a cutting edge 16 that slopes back in a straight line on one edge and is rounded on the opposite edge and brought into junction with the cutting edge to form a point, but leaving between the lever 11 and the commencement of the cutting edge 16 a vertical portion 17, which, after the puncture has been partially made by the point 10 and cutting edge, and the lever lies nearly horizontal, as in Fig. 2, begins to press against the metal being pushed inward to make the opening and crowds it firmly against the vertical wall A⁷ of the can, 15 against the resistance of the standard 10, close to which the can has been placed, leaving an unguarded opening between the side flanges of the opening and the flange pressed against the wall as described, the unguarded opening being numbered A⁶. The member 12 has a bend 18 therein, so that the member 15 will stand vertically beneath the edge of the lever 11, as shown, to receive the full thrust of the lever upon the member 15 instead of upon the rivets 12^a.

At a point on the lever 11 spaced rearwardly from the position of the member 12 is a vent cutter 19, secured to the lever by rivets 19^b; the free extremity of this vent cutter being brought to a point 19^a, as shown, this member 19 also having a bend that brings the point directly beneath the lever, to relieve the rivets of the strain engendered by cutting through the metal of the top wall of the can.

In use, if it is desired to cut the top of the can around the rim in the ordinary way, the opener is used in the position shown in Fig. 4, without the standard 10, as, by standing the lever vertically, with the point of the cutter 14 bearing against the top wall of the can near the rim A⁸ and subjected to a violent pressure downward by hand, or to a blow from a hammer, to make an opening wide enough to permit of the tool being turned downward with the lever about horizontal and the lower edge of the prong 13 resting on the top wall or upon the top and the rim A⁸; then, with the edge 13^a having a bearing upon the top of the can, the lever is lifted, bringing the cutting edge of the member with a cutting force against the under side of the top wall of the can; and when the cut is made as far as it can be with the member 13 in its initial position, the lever is lowered and the tool moved along to give the member 13 another bearing against the top, when the lift of the lever is repeated, and a further cut is made by the knife edge of the part 14; and so on until the extent of the cut in the top is completed.

But if it is desired to make only a slight opening in the edge of the can for the outflow of liquids like evaporated milk, the can is placed on the horizontal member 10^a of

the standard 10, with the lug or stud 11^a in the proper hole 10^b in the standard, and the vertical wall of the can close against the edge of the standard, as shown in Figs. 1 and 2. The member 13 is open at the rear of one side, as shown in Figs. 1 and 2, so that when the lever is in working position and ready to make a puncture, as shown in Fig. 1, the standard 10 will lie between the lip 13^b of the member 13 and the adjoining face of the member 12, and thus be held in position, unable to be moved sidewise. A downward movement of the lever 11 begins to force the cutting point of the cutter 15 into the metal of the top and gradually cuts an oblong opening, the edges of the top adjacent the cut being pressed downward and inwardly into the can and forming opposed flanges A⁴, as shown in Figs. 2, 5, and 6. When the square shoulder 17 reaches the opening, the shoulder will press the metal in front of it sideways firmly against the vertical wall A⁷ of the can, as shown in Fig. 6, tearing its edges from the flanges A⁴, and leaving a corner A⁶ unprotected by any flange, so that, unimpeded by any downwardly projecting wall or flange, all the fluid contents of the can are free to flow out, leaving the can entirely empty, whereas, were a mere downward movement of the point and knife 16 of the member 15 to make the entire opening, there would be left an opening having both side and end walls, so that were the can even completely reversed bottom side up, some of the fluid would remain in the can. It will be noticed that the movement of the lever in making this discharge opening, and with it, the movement of the cutter 15, is downward, in direct contrast to the cutting movement when the blade 14 is being used, as above described.

It is a well-known fact that if a small opening is made in a closed vessel, fluid contents therein cannot freely flow out of the vessel unless there is another opening called a vent made at a point somewhat removed from the first opening. To furnish this vent, the member 19 reaches the top of the can before the opening made by the member 15 is completed, and at a point removed from the side of the can where the discharge opening is being made, makes another puncture, as shown by the position of the member 19 in Fig. 2 when the lever 11 has been brought to a horizontal position, the second opening being comparatively small as compared with the discharge opening.

If, however, it is desired to make but a small opening or vent in the can, the can may be placed on the part 10^a with the side wall of the can considerably removed from the standard, as shown in Fig. 3, and the lever depressed, as before, the can being then out of the reach of the cutter 15.

It is apparent that in the device shown

and described herein, I have provided for the purpose of the invention a very simple, compact, and useful tool, which might, however, without departing from the spirit of the invention be much changed from the precise 5 form of structure shown and described.

Having now shown and described my invention, what I claim is:

1. An implement for opening cans comprising a bar having a pair of spaced cutting points thereon adapted to cut openings in the can at diverse places by an inward bending of the wall of the can, one of the cutters being arranged to leave a portion of the wall 10 free from the inward bend of the substance of the wall, and the other to make an air vent in the wall.
2. An implement for opening cans comprising a bar having a cutting point thereon adapted to puncture a can by an inward bending of the wall of the can, but leaving a portion of the opening free from the flange made by such bending.
3. An implement for opening cans comprising a bar having a shank projecting angularly therefrom which has a cutting point at the outer end thereof and a sharp edge along the portion of the side of the shank, the entire shank being adapted to 25 make an opening in the wall of the can by bending a portion of the wall inwardly and to force a portion of the bent portion or flange against the wall so as to leave a part of the opening unimpeded by the flange.
- 35 4. An implement for opening cans comprising a lever having a cutting member on

the lower side thereof, a support for the lever by the side of the can, the cutting member being adapted to make an opening through the wall of the can by bending a part of 40 said wall inwardly to form a flange and to force a portion of the flange against the wall against the resistance of the support for the lever.

5. An implement for opening cans comprising a lever having a cutting member thereon adapted to make an opening through the wall of the can by a stroke of the lever, a pivotal support for the lever adjacent the can, and means for adjusting 45 the connection of the lever with the support.

6. An implement for opening cans comprising a lever having a cutting member thereon adapted to make an opening in the can by a stroke of the lever, a support for 50 the lever, and means for detachably securing the lever to the support.

7. An implement for opening cans comprising a lever having a cutting member thereon adapted to make an opening in the 55 can by a stroke of the lever, a support for the lever, and means for detachably and adjustably securing the lever to the support.

8. An implement for opening cans comprising a lever having a cutting member 60 thereon adapted to make an opening in the can by a stroke of the lever, a support for the lever, means for detachably securing the lever to the support, and means for preventing the detachment of the lever while employing in cutting the opening in the can. 70

ALBERT C. BURKE.
